UNITED STATES PATENT OFFICE.

OSCAR H. PIEPER AND ALPHONSE F. PIEPER, OF ROCHESTER, NEW YORK.

DENTAL CUSPIDOR.

1,377,433.

Specification of Letters Patent. Patented May 10, 1921.

Application filed May 2, 1919. Serial No. 294,246.

To all whom it may concern:

Be it known that we, OSCAR H. PIEPER and ALPHONSE F. PIEPER, both of Rochester, in the county of Monroe and State of New York, have invented certain new and useful Improvements in Dental Cuspidors; and we do hereby declare the following to be a full, clear, and exact description of the same, reference being had to the accompanying drawings, forming a part of this specification, and to the reference-numerals marked thereon.

Our present invention has for its object to provide a cuspidor fixture of the type used by dentists which is adapted to be mounted or arranged in proximity to the dental operating chair and comprises a novel means of mounting the flush pipe whereby it may be utilized as the support for certain of the auxiliary devices and as such rendered capable of rotative adjustment to any desired position about the rim of the cuspidor bowl. In carrying out our invention, we have provided a fixture on which the cuspidor bowl is supported which also provides the drain or waste pipe therefor and carries the water supply pipe with which the flush pipe is connected, the point of union of the two parts having specially constructed bearings forming broad co-operating faces with means for securing them in engagement whereby the flush pipe, without other means of support, may be firmly locked in any position of adjustment, thus permitting the flush pipe to be used as the support for such devices as the basin, drinking water glass, saliva extractor and finger bowl. To these and other ends the invention consists in certain improvements and combinations of parts, all as will be hereinafter more fully described, the novel features being pointed out in the claims at the end of the specification.

In the drawings:

Figure 1 is a side elevation of a fixture illustrating one embodiment of our invention;

Fig. 2 is a top plan view, and

Fig. 3 is an enlarged central vertical section showing the means of attaching the flush pipe.

Similar reference numerals throughout the several views indicate the same parts.

Dental cuspidor fixtures must be so designed as to enable the bowl, comprising the cuspidor proper, to be located in a fixed

position at the side of the dental chair opposite that occupied by the dentist when operating upon a patient and sufficiently close to the chair to be at all times within convenient reach of the patient. Because of this proximity it is very desirable to provide means for adjusting the auxiliary devices which are necessarily located at the side of the bowl whereby they may be easily adjusted bodily into the most convenient position either to provide space at that side of the operating chair for the dentist's assistant or for the greater convenience of the dentist himself. To this end, we have provided a structure in which the so-called auxiliary devices may be adjusted concentrically to the rim of the cuspidor bowl and the structure as a whole simplified by mounting these parts on the flush pipe.

In the illustration, we have shown the cuspidor having a circular rim and provided with a central drain mounted on a support in the form of a hollow arm which preferably forms the waste pipe and has the upwardly opening end in which the bowl is seated and secured by the collar 3.

On its lower side, the support is provided with the water discharge opening 4 which is located centrally of the rim of the bowl, the water being conducted to the opening by a pipe 5 and its flow controlled by a suitable valve 6.

The flush pipe 7 discharges at its upper end, through one or more nozzles 8, into the cuspidor and from this point leads downwardly and inwardly beneath the support and into communication with the discharge opening 4. On the upper end of the pipe there may be mounted any of the usual auxiliary devices, those shown being the basin 9 and the glass 10.

At the point where the flush pipe is attached to the support, suitable bearing faces are provided which are of sufficient diameter and breadth to enable the pipe to be held securely in its vertical position whether it is locked rigidly or merely held sufficiently tight to prevent leaking at the joint and yet capable of being shifted from one position of adjustment to another. In the present illustration, the bearings are shown as comprising a nipple 15 projecting downwardly from the support having an interior conical surface 16 and a horizontal face 17 and a head 18 on the lower end of the flush pipe having an annular shoulder 19, which abuts

the face 17, and a conical portion 20 fitting against the surface 16. One of these two parts is threaded and the other carries a nut by means of which the head may be locked 5 to the support and a convenient way of arranging these parts is to make the nipple separate from the support and secure it in position thereon by screw threads 21 in which event the nipple can be provided with 10 the shoulder 22 for supporting the nut 23 and the head 18 will be threaded to co-operate with the interior threaded portion of the nut. By loosening the nut, the flush pipe may be adjusted to any desired position 15 around the periphery of the bowl and by reason of the broad engaging surfaces of the parts, the pipe will always be held upright and may be easily clamped rigidly in any desired position.

20 We claim as our invention:

1. In a cuspidor fixture, the combination 25 with a bowl having a substantially circular rim and provided with a discharge opening, a support for the bowl and a fluid supply pipe having a discharge end on the support disposed centrally of the rim of the bowl, of a flush pipe discharging into the bowl at its upper end and extending downwardly therefrom and at its lower end communicat- 30 ing with the discharge end of the supply pipe, a basin carried by said flush pipe, said support and lower end of the flush pipe having bearing faces coöperating to support the flush pipe and basin and means for securing the flush pipe to the support to hold 35 said faces in engagement.

2. In a cuspidor fixture, the combination 40 with a bowl having a substantially circular rim and provided with a discharge opening, a support for the bowl and a fluid supply pipe having a discharge end on the support disposed centrally of the rim of the bowl, of a flush pipe discharging into the bowl at its upper end and extending downwardly 45 therefrom and at its lower end communicat-

ing with the discharge end of the supply pipe, a basin carried by said flush pipe and discharging into said cuspidor, said support and lower end of the flush pipe having circular bearing faces coöperating to support 50 the flush pipe and basin and permit rotative adjustment thereof around the rim of the bowl and means for securing the flush pipe to the support to clamp said surfaces in engagement.

3. In a cuspidor fixture, the combination 55 with a circular bowl having a discharge opening, a hollow support having an upwardly extending open end supporting the bowl and communicating with the opening 60 therein and also provided with a downwardly opening fluid supply passage disposed centrally of the bowl, of a flush pipe for the latter discharging thereinto at its upper end and having its lower end communicating with said supply passage, a basin supported by said flush pipe, said support and lower end of the flush pipe being provided with bearing faces adapted to support the pipe and basin and permit rotary 65 adjustment thereof, one of said parts being provided with a thread and the other carrying a nut coöperating therewith and serving to lock said faces in engagement.

4. In a cuspidor fixture, the combination 70 with a bowl having a liquid discharge opening, of a support therefor communicating with the discharge opening in said bowl and provided with a conduit through said support, a passageway within said support, a 75 flush pipe disposed close beside the bowl in communication with said passageway, and adapted to discharge into the bowl, a basin 80 on said flush pipe and a single adjustable bearing between said support and flush pipe carrying the flush pipe and basin and adapted to permit movement of said basin about the edge of the bowl.

OSCAR H. PIEPER.
ALPHONSE F. PIEPER.
